UNITED STATES PATENT OFFICE.

EMIL KLAHN, OF WEEHAWKEN, NEW JERSEY, ASSIGNOR TO BARNEY & BERRY,
INCORPORATED, OF SPRINGFIELD, MASSACHUSETTS, A CORPORATION OF MASSA-
CHUSETTS.

METHOD OF MAKING ROLLERS OR WHEELS.

978,036.

Specification of Letters Patent.

Patented Dec. 6, 1910.

Application filed October 7, 1908. Serial No. 456,677.

To all whom it may concern:

Be it known that I, EMIL KLAHN, a citizen of the United States, residing at Weehawken, in the county of Hudson and State 5 of New Jersey, have invented certain new and useful Improvements in Methods of Making Rollers or Wheels, of which the following is a specification.

This invention relates to the method of 10 making rollers for roller skates and the like.

It has for its object the provision of a metallic roller of great strength and lightness which can be produced rapidly and at small cost.

15 In the accompanying drawings, forming part of this specification, I have illustrated the invention as embodied in a roller adapted for ball bearings, but it is obvious that such bearings may be dispensed with and 20 plain bearings employed instead.

In the drawing, Figure 1 is a view of a metal blank for the formation of the rim and web of the roller. Fig. 2 is a sectional view showing the blank formed into a cup 25 with the center punched out. Fig. 3 is a sectional view of the web of the roller immediately after being punched out of the cup shown in Fig. 2. Fig. 4 is a sectional view of the rim of the roller which is formed 30 from the side or wall of the cup shown in Fig. 2. Fig. 5 is a sectional view through the web and rim arranged in position for the operation of the assembling dies. Fig. 35

6 is a sectional view of the form of hub used in the roller when considered with ball 40 bearings. Fig. 7 is a sectional view through the roller after the action of the assembling dies, with the die shown in position above and below the roller.

45 The improved roller forming the present invention comprises a rim, a hub, and a web connecting the rim and the hub. The rim and web are preferably formed from sheet metal for the sake of cheapness, and the hub may be a forging, a casting, or it may be turned from a bar as preferred. In the production of the improved roller, the rim and web are preferably obtained from a circular blank of steel of suitable gage. This 50 blank is formed by dies into a cup, as illustrated in Fig. 2, the side or wall 2 of the cup being parallel to its axis, as shown, and the base 3 being formed with a central opening

4, and being raised in the center for reasons which will presently appear. After the formation of the cup as shown in Fig. 2, the base or bottom of the cup is punched out and presents the form shown in Fig. 3. The side or wall of the cup 2 is then grooved circumferentially on its inner surface as shown 55 at 5 in Fig. 4, and after the grooving operation is ready to serve as the rim of the roller. The rim and web are brought into proper relation as shown in Fig. 5, and the hub 6 is then introduced within the opening 60 65 of the web. The three parts are then assembled between coöperating dies 7 which act upon the web 3 to flatten it and expand it both outwardly and inwardly, so that it completely fills the groove 5 formed in the 70 inner surface of the rim of the roller and a smaller groove 8 formed on the outer surface of the hub 6. The relation of the parts after the action of these dies is clearly shown in Fig. 7. 75

In the construction of the improved roller, it will be understood that the material used in forming the web and the rim must be of sufficient ductility to be readily formed by dies, whereas the hub must be made of 80 material hard enough to withstand wear. Ordinarily, I use hot rolled sheet steel for the manufacture of the rim and web, and for the hub, I use machine steel which is turned to the proper form, and case-hardened to make it stand wear. 85

Having thus described my invention, what I claim is new, and desire to secure by Letters Patent is:

The method of producing a roller for 90 roller skates or the like consisting in forming a cup with the bottom raised in the center, punching the bottom out of said cup, forming a central hole in the bottom of said cup, introducing the punched out bottom of 95 the cup within a wall of the cup, introducing the hub into the opening formed in the center of the bottom of the cup, and expanding the bottom of the cup into engagement with the wall thereof and the hub. 100

In testimony whereof, I have signed my name in the presence of witnesses.

EMIL KLAHN.
